CLAIM

The ornamental design for a carrying case for tape cassettes, as shown and described.

DESCRIPTION

FIG. 1 is a front perspective view of a carrying case for tape cassettes showing my new design, the opposite sides not shown being identical to the sides shown;

FIG. 2 is a front perspective view thereof with one side open;

FIG. 3 is a rear perspective view thereof with the other side open; and

FIG. 4 is a bottom plan view of FIG. 1.

FIG. 1

FIG. 2

FIG. 3

FIG. 4
